TRANSMISSION SYSTEM

Frank Conrad, Pittsburgh, Pa., assignor to Westinghouse Electric & Manufacturing Company, a corporation of Pennsylvania

Application January 17, 1930. Serial No. 421,471

10 Claims. (Cl. 250—33)

My invention relates to a transmission means and, more particularly, to an antenna system and a method of transmitting radio signals.

When referring to radio waves we frequently consider them as comprising two waves, a ground wave and sky wave, the sky wave being that portion of the wave received by reflection from the Kennelly-Heaviside layer and the ground portion being that portion which follows along the earth's surface in its travel from the transmitter to the receiver. These terms will be used throughout the following description in explaining the objects and purposes and the manner of operation of my invention.

In using a vertical transmitting antenna, the local signal is due to the radiation of the ground wave component of the transmitted wave, whereas distant signals depend considerably on the sky wave component or, in other words, the radiation initially at an angle of elevation, this vertical component subsequently descending as it moves outward from the antenna by reason of reflections from Kennelly-Heaviside layer, and also by reason of the fact that the waves travel slower at the surface of the earth than in the upper atmosphere.

The pattern of a single vertical transmitting antenna is a circle, points at equal distances from the center of which representing substantially the same field intensity. In the vertical plane the magnetic field may be represented by a semi-circle. In order to secure or obtain greater intensities at distant receiving stations, it will be necessary to increase the power output or the power generated at the transmitting station. However, this will also result in a great increase in the local intensities or local signal strength which is both undesirable and unnecessary.

As is well known to those who are acquainted with the operation of receiving sets, broadcast reception is much more efficient during the evening than during the day by reason of the fact that lower strata of atmosphere become ionized during the day and the radio waves are more or less absorbed. This absorption reduces the effect of the vertical component or sky wave, and reception during the day arises mostly from the ground wave.

It is an object of my invention to attain an increase in the distant signal strength without increasing signal strength in the vicinity of the broadcasting station.

It is another object of my invention to extend the range of influence of a vertical component of a transmitted wave whereby radio reception in

the evening may be extended to greater distances.

Another object is to extend the influence of the ground wave or horizontal component for daylight transmission.

A further object of my invention is to provide means for selectively extending the influence of either the vertical component or the horizontal component of a transmitted wave.

An additional feature of my invention resides in the method for accomplishing the above results.

Further features of my invention will be disclosed in the following description taken in conjunction with the accompanying drawings, wherein

Figure 1 represents a field intensity pattern in the horizontal plane for a single vertical transmitting antenna.

Figs. 2 through 8 represent field intensity patterns in the horizontal plane for an antenna system involving my invention utilizing four vertical antennæ operating in synchronism for various spacings of the antennæ.

Fig. 9 represents a field pattern in a horizontal plane for a single vertical antenna, and for eight vertical antennæ operating in synchronism.

Fig. 10 represents a field pattern in a vertical plane for a single vertical antenna, and for eight vertical antennæ operating in synchronism.

Fig. 11 shows a curve illustrating field intensity at a constant distance in vertical and horizontal directions about four vertical antennæ with currents in adjacent antennæ 90° out of phase.

Fig. 12 is a curve showing field intensity at a constant distance in vertical and horizontal planes about eight vertical antennæ with currents in adjacent antennæ 45° out of phase.

Figs. 13 and 14 are diagrams illustrating the mathematical basis for my method of transmitting.

Fig. 15 illustrates schematically a four antenna system embodied in my invention.

If the ratio of horizontal radiation to the radiation of the vertical component can be decreased then the desired decrease of the ratio of local to distant signal strength may be attained. Broadly speaking, this is accomplished by using an arrangement and spacing of a plurality of vertical antennæ fed with currents from a transmitter, the currents in the antennæ being in time phase. In an arrangement of this order interference between waves from the various antennæ will reduce the horizontal field strength and in this manner cut down the radiation resistance of the antenna system in a horizontal direction.

This will result in an increase of current to the antennæ with a corresponding increase in the vertical component of the wave to such a value that the energy output from the system will be substantially the same as when using a single vertical antenna. This can be accomplished by running a transmission line 6 (Fig. 15) to a central point 7 and running feeders 8, 9, 10 and 11 from this point to the individual antennæ 12, 13, 14 and 15. It will thus be obvious that the influence of the vertical component has been greatly extended without increasing local signal strength.

To illustrate the above feature, calculations were made of the field intensity in the horizontal plane in different directions from four vertical antennæ in which the currents were maintained in the same time phase and the antennæ were located on corners of squares of different dimensions to determine how much the interference between the transmitted waves reduced the horizontal component. The patterns obtained, as well as the pattern for a single antenna with the same total current, are plotted to the same scale in Figs 1 to 8. The calculated values from which these patterns were plotted are set forth below:

Table 1

No. of poles	Side of square	Diameter of circle	Field intensity		Area of intensity squared proportional to energy
			Maximum	Minimum	
1	0 Meters	0 Meters	.4	.4	2,500
4	.3535λ	.5 λ	.178	.120	120
4	.4375λ	.619λ	.066	.015	15
4	.5 λ	.707λ	.008	.006	6
4	.531 λ	.75 λ	.023	.010	.6
4	.547 λ	.775λ	.015	.007	.1
4	.562 λ	.795λ	.015	.009	.04
4	.625 λ	.885λ	.009	.004	12

The patterns represent field intensities, whereas the last column in the tabulated values represents the area of the patterns squared, which values are proportional to the energy output of the antenna system in the horizontal plane. The results show that the minimum horizontal radiation occurs when the four poles are on the corners of a square .562λ on a side.

Tests made at 40 meters for a four antenna system indicate that intensity patterns similar to those calculated are obtained and that there is a noticeable increase in distant signal strength when the transmitter is shifted from a single antenna to the four pole antenna system.

For the condition of minimum horizontal radiation with four antennæ the intensity, as clearly illustrated in Fig. 7, varies considerably in different directions. To obtain a more nearly circular intensity pattern, calculations were made for an eight antenna system. A representative pattern obtained for the eight antennæ on a circle of diameter .707λ meters is shown in Fig. 9 to the same scale as Fig. 1. The horizontal distribution of intensity is illustrated by the corner curve 1 for the eight pole system, and by the outer curve 2 for a single pole system. Calculations were also made for an eight antenna system to determine the vertical component. The general shape of the intensity variation in a vertical plane is shown in curve 3 Fig. 10, together with the curve for the single vertical antenna carrying the same total current as the eight an-

tenna system. This figure clearly shows the increased ratio of radiation of the vertical component to the horizontal component. It should be realized that when used with a transmitter the total current in the eight antenna system will not be the same as with the single antenna, but will be considerably larger in the case of the eight antennæ due to the decreased radiation resistance. Therefore, the radiation in the vertical direction should be larger and that in the horizontal direction should, if anything be smaller for the eight antenna system, than for the single antenna. The dotted line curve 5 of the figure illustrates this difference, when compared with the curve for the single antenna 4.

For daytime broadcasting it is desirable to obtain the reverse effects, namely, a strengthening of the horizontal component of the transmitted wave and a reduction of the sky wave or vertical component. This result can be accomplished by using an arrangement of vertical antennæ substantially as described above, and throwing the currents in each pair of diametrically opposed antennæ approximately 180° out of phase. This will result in a suppression to a certain extent of the vertical component and an increase in the strength of the horizontal component. For instance, one could use four vertical antennæ spaced equally on a circle of diameter in the neighborhood of $\lambda/2$, with currents in the diagonally opposite poles 180° out of phase and the currents in adjacent poles 90° out of phase. The intensity of the radiation in a given direction in the horizontal plane is equal to the vector sum of the intensity produced by the individual antennæ. This intensity can be represented by the following formula:

$$H = \sum_{n=0}^{n=8} \frac{4\pi hI}{10 \lambda s} \cos \frac{2\pi}{\lambda} \left(ct - s - \frac{\phi \lambda}{2\pi} \right)$$

and the method of calculation is outlined below in conjunction with Fig. 13 of the drawing. For a single vertical antenna

$$H = \frac{4\pi hI}{10 \lambda s}$$

where h =effective height; I =current at base of antenna; λ =wavelength; and s =distance from antenna. For a system of antennæ the phase of each is given by

$$\cos \frac{2\pi}{\lambda} (CT - s - \Delta s_2 - \frac{\phi' n}{2\pi})$$

where C =velocity of propagation, T =time; S =distance from center of antenna system; $\Delta s_2 = s_2 - s$ =approx. $r \cos \alpha$; and $\phi' n$ =time phase lag of current behind phase of reference. For phase of reference let $CT - S = 0$; then lag of antenna field behind phase of reference is

$$\phi_n = \frac{2\pi}{\lambda} r \cos \alpha = \phi' n$$

$r \cos \alpha + \phi' n$. Each antenna will have an in-phase component $H \cos \phi n$ and an out-of-phase component $H \sin \phi n$. Resultant field

$$H_R = \sqrt{\left(\sum_{n=1}^{n=4} H \cos \phi n \right)^2 + \left(\sum_{n=1}^{n=4} H \sin \phi n \right)^2}$$

The intensity of the radiation in a vertical plane at an angle β , for instance, for a four antenna system may be calculated in the following manner, with reference to Fig. 14 of the drawing.

The equation for a single vertical antenna in a direction at an angle of elevation is

$$H = \frac{4\pi hI}{10 \lambda s} \cos \beta$$

where h =effective height; I =current at base of antenna; λ =wave length; S =distance from antenna; and β =angle of elevation. For a system of several antennæ, phase relation must be taken

10 into account. The phase relation is given by

$$\cos \frac{2\pi}{\lambda} (CT - S - \Delta S_n - \frac{\phi'_n}{2\pi})$$

where C =velocity of propagation; T =time, 15 S =distance from center of antenna system, $\Delta S_n = S_n - S$ =(approx. $X^* \cos \beta$)= $r \cos \alpha \cos \beta$; (α =angle in horiz. plane of antenna from X axis; and ϕ_n =time phase lag of current in antenna behind phase of reference. For relative 20 phase relation let $CT - S = 0$ so that angle of lag of antenna field behind phase of reference is

$$\phi_n = \frac{2\pi}{\lambda} S_1 + \phi'_n = \frac{2\pi r}{\lambda} \cos \alpha \cos \beta + \phi'_n$$

25 Each antenna will have an in-phase component $H \cos \phi_n$ and an out-of-phase component $H \sin \phi_n$. The resultant field

$$H_R = \sqrt{\left(\sum_{n=1}^{n=4} H \cos \phi_n\right)^2 + \left(\sum_{n=1}^{n=4} H \sin \phi_n\right)^2},$$

where the summation is algebraic addition.

Consider the field arising from the four pole system above, in the direction of a diagonal. 30 Then the two poles on the other diagonal will have a time phase difference of 180° with respect to each other but no distance phase difference in this direction and their signals will cancel. The other two poles for the horizontal plane in this direction have a time phase difference of 180° with respect to each other and a distance phase difference of 180° which makes the radiation from the two antennæ add in phase. Therefore, for the same antenna current, the horizontal signal in this direction is $\frac{1}{2}$ the signal from a single antenna with the same total current. At an angle of 60 degrees the effective distance phase difference is $\cos 60^\circ \times 180 = 90^\circ$; therefore the signals from the two latter antennæ are 90° out of phase and the vector sum is equal to $1.414 \times \frac{1}{4} = .3535$ times the signal in a single pole with the same total current. For directions between two poles the radiation is slightly greater than in the direction of a diagonal, but the relative proportion of horizontal and upward radiation is the same. Thus the radiation resistance has been reduced to less than half that of a single antenna, so that if the ohmic resistance is small compared to the radiation resistance, the current in the four pole system would actually be about twice that in a single pole antenna giving a horizontal radiation greater than the single antenna and an upward radiation less than the single antenna. An eight pole system with currents in adjacent poles 45° out of phase has the advantage over the four pole system just described in that it gives slightly greater horizontal radiation for the same total current; that is, it reduces the horizontal field less for the same total current; and in that it gives a circular field pattern.

The phase relationships assumed above can be obtained by making the transmission lines

12, 14, 15 to the individual antennæ of different length or by loading the lines by different amounts, preferably keeping the surge impedances approximately the same.

It is evident that the same antenna system can be used with either of the above schemes, and that with two separate transmission systems and remote control switching, it would be possible to change rapidly from one to the other.

While I have described my invention as embodied in antenna systems comprising four antennæ and eight antennæ, it is obvious that any number of antennæ might be used with similar results and I do not wish to be limited to the specific details outlined above only insofar as my invention may be limited by the prior art.

I claim as my invention:

1. In a system for radiating electro-magnetic energy eight vertical antennæ, said antennæ being substantially uniformly disposed on the circumference a circle of diameter substantially .707 of the wave length of the energy to be transmitted and means for energizing said antennæ cophasely.

2. The method of transmitting electro-magnetic signals with a system incorporating eight vertical antennæ arranged at the vertices of a regular octagon which comprises impressing periodic electro-magnetic disturbances, with a phase displacement of 45° between successive antennæ, on said antennæ.

3. The method of transmitting electro-magnetic signals with a system incorporating n vertical antennæ, said antennæ being disposed at the vertices of a regular polygon which comprises impressing periodic electro-magnetic disturbances, with a phase displacement of

$$\frac{2\pi}{n}$$

between successive antennæ, on said antennæ wherein n is the number of said antennæ.

4. The method of transmitting electro-magnetic signals with a system incorporating a plurality of vertical antennæ, said antennæ being disposed at the vertices of a regular polygon which comprises impressing periodic electro-magnetic disturbances, with a phase displacement of 180° between antennæ displaced by an angle of 180° on said antennæ.

5. In a system for radiating electro-magnetic signals, four vertical antennæ disposed substantially at the vertices of a square of which the sides have a length of substantially .562 of the wave length to be transmitted and means for energizing said antennæ cophasely.

6. In a system for radiating electro-magnetic signals, four vertical antennæ disposed at the vertices of a square of which the sides have a length of greater than .547 of the wave length to be transmitted and less than .625 of the wave length to be transmitted and means for energizing said antennæ cophasely.

7. The method of broadcasting electro-magnetic signals with apparatus of a type incorporating eight vertical antennæ disposed at the apices of a regular octagon which comprises the steps of impressing periodic electro-magnetic disturbances during the day time cophasely on each of said antennæ, and impressing disturbances, with a phase displacement of 45° between successive antennæ on said antennæ during the night time.

8. In a system for radiating electro-magnetic energy, eight vertical antennæ, said antennæ be-

* X =distance in direction of X -axis, of antenna pole from center of system. X -axis in this figure corresponds to line S in the figure for the horizontal plane.

ing substantially uniformly disposed on the circumference of a circle of diameter substantially .707 of the wave length of the energy to be transmitted, and means for alternatively energizing said antennæ cophasely or with a phase displacement between successive antennæ of 45°.

9. The method of broadcasting electro-magnetic signals with apparatus of a type incorporating n vertical antennæ arranged at the apices of a regular polygon having n sides, which comprises the steps of impressing periodic electromagnetic disturbances cophasely on said antennæ during certain periods of the day and impressing disturbances, with a phase displacement of

$$15 \quad \frac{2\pi}{n}$$

$$20 \quad \frac{4\pi}{n}$$

$$25 \quad \frac{6\pi}{n}$$

$$30 \quad \frac{8\pi}{n}$$

$$35 \quad \frac{10\pi}{n}$$

$$40 \quad \frac{12\pi}{n}$$

$$45 \quad \frac{14\pi}{n}$$

$$50 \quad \frac{16\pi}{n}$$

$$55 \quad \frac{18\pi}{n}$$

$$60 \quad \frac{20\pi}{n}$$

$$65 \quad \frac{22\pi}{n}$$

$$70 \quad \frac{24\pi}{n}$$

$$75 \quad \frac{26\pi}{n}$$

between successive antennæ, on said antennæ during certain other periods of the day.

10. The method of broadcasting electro-magnetic signals with apparatus of a type incorporating n vertical antennæ arranged at the apices of a regular polygon having n sides, which comprises the steps of impressing periodic electromagnetic disturbances cophasely on said antennæ during the daytime and impressing disturbances, with a phase displacement of

$$\frac{2\pi}{n}$$

between successive antennæ on said antennæ during the night time.
